UNITED STATES PATENT OFFICE.

JAMES E. GROSJEAN, OF LIMA, OHIO.

METHOD OF MAKING VULCANIZED PRODUCTS.

Application filed December 30, 1919. Serial No. 348,295.

To all whom it may concern:

Be it known that I, JAMES E. GROSJEAN, a citizen of the United States, residing at Lima, in the county of Allen and State of Ohio, have invented new and useful Improvements in Methods of Making Vulcanized Products, of which the following is a specification.

My present invention relates to improvements in the art of manufacturing heels for boots or shoes, and similar products from rubber or other vulcanizable material whereby a heel or similar product having great durability, and wear-resisting, anti-slipping, and other desirable properties may be manufactured rapidly and at relatively small expense. The invention is particularly applicable to the manufacture of heels for boots or shoes which comprises an attaching base of fabric or equivalent tough material adapted to receive and securely hold the heads of nails which serve to secure the heel to the boot or shoe, a textile or equivalent cord or thread containing tread, and a body of vulcanizable material, preferably rubber, these constituent parts of the heel being assembled, then subjected to compression and heat in a mold or die, the cavity of which is of such form as to give the desired shape to the finished heel and while the heel is held under compression in such shape it is cured or vulcanized, whereby the constituent parts of the heel are securely united and the heel as a whole becomes permanently set in its final form.

In the accompanying drawing, in which the invention is shown applied to the manufacture of heels of the general character just described,

Figures 1 and 2 are perspective views each showing the constituent parts used to make up a heel, prior to the introduction of the same into the mold,

Figure 3 is a diagrammatic view of a mold showing the parts used in the making of the heel, introduced therein but prior to compression of such parts, and

Figure 4 is a view similar to Figure 3, but showing the mold closed and indicating the manner in which the heel is squeezed or compressed into its final form.

While the method provided by the present invention is applicable generally to the manufacture of vulcanizable products of various forms and kinds adapted to various uses, the method will be herein shown and

described as applied to the manufacture of heels as one example of the manner in which the invention may be carried out. In this particular application of the invention, the heel is made up of an attaching base 1, a tread 2 and a body 3, the latter preferably conforming substantially in size and outline to that of the heel to be produced, while the base 1 may conform substantially to the outline of the body but is somewhat smaller so that the body forms a margin which projects from the periphery of the base, and the tread 2 preferably conforms substantially to the outline of the body but is somewhat smaller than the base so that the body forms a relatively wider margin around the periphery of the tread. The base 1 and the tread 2 are preferably of such character that they retain substantially their original form and size when subjected to compression and heat while the interposed body 3 is of such a character that it is capable of being molded under compression and heat and to become permanently set by vulcanization or curing. In practice, it is preferable to form the base 1 from a suitable number of plies of tough material through which the securing nails for the heel may be driven and which will strongly secure the nail heads against pulling through the base, plies of canvas or other textile or woven fabric coated with vulcanizable material, preferably rubber, being most suitable for this purpose. The body 3 is preferably composed of one or more sheets of raw or uncured rubber to which the flat sides of the base and tread will adhere with sufficient firmness to permit handling without detachment or displacement of the parts when the base and tread are pressed against its opposite sides. The tread is preferably composed of layers of a cord or fabric structure and intervening layers of vulcanizable material. Preferably, the tread is composed of the twisted cord or fabric structure reclaimed from used or discarded cord or fabric automobile tires, it being necessary in such cases only to remove the rubber which covers the cord or fabric structure and to cut the cord or fabric structure into strips of a width corresponding substantially to the thickness of the tread, layers or strips of vulcanizable material, preferably rubber, being interposed between the layers of cord structure or fabric, the edges of the layers and also the ends of the cords or the treads of the fabric being pre-

sented to the wear surface of the tread. This cord or fabric structure may however be made up from fresh or raw stock as desired.

5 In performing the method as applied to the manufacture of heels of the character described, the blank composed of the base 1, the tread 2 and the body 3 in adhering relation, as shown in Figures 1 and 2 is placed 10 in a mold or die 4, which may be of any suitable construction but provided with a cavity 5 which conforms in shape and size to the finished heel. When the blank is placed in the mold, as shown in Figure 3, 15 the tread 2 will rest on the bottom of the mold or die cavity, the body 3 will approximately fit within the periphery of the mold cavity, and the base 1 will project some distance above the top of the mold or die. The 20 next step in the method is performed by forcing the upper member or top 6 of the mold or die down upon the body of the mold or die, the top of the base 1 fitting flatwise and evenly against the under flat side of the 25 mold or die member 6. This operation squeezes the base and tread into the upper and lower sides of the interposed body, the material of the body which is thus squeezed from between the base and tread flowing to 30 the periphery of the mold and filling the same vertically to form a finishing edge 3^a for the heel. Any surplus rubber or material from the body will be forced out of the top of the mold after the mold has been 35 completely filled.

The final step in the method consists in vulcanizing or curing the heel to strongly unite its constituent parts and to permanently set the heel in proper form and condition for use. This may be effected advantageously by heating the heel or product while it is held under compression in the mold, the mold being for example steam heated and effecting vulcanization of the 40 material or rubber composing the heel. After vulcanization or curing has been completed, the heel is finished and may be removed in any suitable way from the mold.

The procedure in manufacturing other 45 products by the method constituting the present invention may be substantially the same as that hereinbefore described for the manufacturing of heels.

The manufacture of heel and other products by the method hereinbefore described offers many important practical advantages over methods heretofore used for such purposes. The constituent parts of the product may be easily and quickly cut or punched 50 into the proper shape and sizes and these parts when pressed together in their correct relation will adhere to one another with sufficient firmness to enable the blanks thus formed to be handled without separation or 55 displacement. The step of squeezing or

compressing the blank in a mold or die of the proper shape and size brings all the constituents of the product into their correct ultimate relation and it also gives the product its ultimate exterior form and size. Vulcanization or curing of the product while maintained under compression gives the product its finished form and condition and it firmly unites the constituent parts of the product. As applied to the manufacture of 70 heels for boots and shoes, the expense of manufacture is substantially reduced and a superior product is obtained, particularly as compared with heels of the class in which nail receiving washers are embedded in the 75 rubber composing the body of the heel. The tough fabric or equivalent base receives the nails which secure the heel upon the shoe and by its nature, this base enables the securing nails to be driven simultaneous and 80 at any desired points. This base, when produced in products other than heels may serve to attach such products to supports or other objects.

I claim as my invention:—

1. The method of making heels for boots and shoes which comprises assembling an attaching member and a tread member at the opposite sides of a body of vulcanizable plastic material of relatively larger area, said 95 attaching and tread members comprising plies of textile material and intervening vulcanizable material, compressing together said attaching and tread members and body, while the body is confined peripherally and 100 under sufficient pressure to squeeze said attaching and tread members into the opposite sides of said body and to force a portion of the material outwardly from the space between said members beyond the peripheries of said members and to cause the material so forced to spread in both directions transversely of the direction of outward flow to 105 form margins of substantial width around the peripheries of the attaching and tread members, and vulcanizing the resulting product to unite the attaching and tread members to the intervening body and surrounding margins.

2. The method of making heels for boots and shoes which comprises assembling a composite tread of textile material and intervening layers of vulcanizable material to a body of vulcanizable material, the layers of the tread being presented edgewise to said body, compressing said tread and body sufficiently to squeeze the tread into said body and vulcanizing the resulting product to unite said intervening layers of vulcanizable 110 material of the tread with said body.

3. The method of making heels for boots and shoes which comprises assembling an attaching member and a tread at the opposite sides of a body of vulcanizable plastic material of relatively larger area, the attach- 115

- ing member having fabric plies extending parallel to the plane of said body and the tread having fabric plies which extend transversely to the plane of said body, com-
5 pressing together said member, tread and body while the body is confined peripherally and under sufficient pressure to squeeze said member and tread into the opposite sides of said body and to force a portion of the ma-
10 terial of the body outwardly from the space between said member and tread and to spread the same in both directions trans-
versely of the direction of outward flow to form margins around the peripheries of said
15 member and tread, and vulcanizing the re-
sulting product to unite the plies of the at-
taching member and tread respectively to
said body.
4. The method of making heels comprising
20 placing an attaching member and a tread both containing layers of textile material and intervening layers of vulcanizable material at opposite sides of a body of rubber of relatively larger area, the layers of the attaching member extending upwardly to 25 the plane of said body and the layers of the tread extending transversely to the plane of said body, compressing together said member, tread and body while confined peripherally and under sufficient pressure to 30 squeeze said member and tread into the opposite sides of said body and to force a portion of the material composing said body outwardly from the space between the at-
taching member and tread to the peripheries of said member and tread, and vul-
canizing the resulting product to unite the intervening layers of vulcanizable material of the attaching member and tread with 35 said body.
- In testimony whereof I have hereunto set my hand in presence of two subscribing wit-
nesses.
